BATHTUB READING RACK

Stanley G. Barker, 607 Madison St., Joliet, Ill. 60435

Filed Feb. 14, 1967, Ser. No. 5,810

Term of patent 14 years

(Cl. D33—3)

FIG. 2 is a rear elevation thereof;

FIG. 3 is a top plan view of the reading rack of FIG. 1;

FIG. 4 is a side elevation thereof; and

FIG. 5 is a section taken along the line 5—5 in FIG. 3.

I claim:

The ornamental design for a bathtub reading rack, substantially as shown.
